ATION OF PENNSYLVANIA.

CUSHION.

No. 897,541.

Specification of Letters Patent.

Patented Sept. 1, 1908.

Application filed July 5, 1907. Serial No. 382,150.

To all whom it may concern:

Be it known that we, JOHN B. KILBURN and EDWARD G. BUDD, citizens of the United States, residing at Philadelphia, in the county 5 of Philadelphia and State of Pennsylvania, have invented certain new and useful Improvements in Cushions, of which the following is a specification.

This invention relates to cushions and has 10 reference particularly to cushions of the type adapted for use in car-seats.

The object of the invention is to effect certain improvements in the construction of cushions for this use, to the end that a cushion 15 is produced which is quite soft, which is strong and durable, which can be manufactured at low cost, and which is constructed largely of metal, so that it is practically fire-proof.

20 In accordance with the invention, the cushion has a metallic frame consisting of four frame-members secured together at their ends. Some or all of these frame-members are sheet-metal strips, which are pressed to 25 the desired form, and these frame-members support a plurality of spiral springs, which serve to yieldingly sustain the covering of the cushion. These sheet-metal frame-members are of channel-section, and the springs sup- 30 ported thereby are mounted upon the bottoms of these channels; for this reason, the springs may be of increased length, resulting in making the cushion softer and more durable on account of this greater length of 35 spring. The size of these sheet-metal frame-members is such that the sides thereof serve to support the spiral springs and preclude excessive lateral movement thereof. In order to increase the strength of the frame-mem- 40 bers, a plurality of metallic braces are preferably employed, extending across the frame-members and secured at their ends to integral flanges formed at the lateral edges thereof. Preferably these members of the frame 45 are formed to provide grooves at their outer edges adapted to receive strips of wood, paper or similar material, to which the edges of the covering material of the cushion may be secured by tacks. The central portion of the 50 cushion is supported by spiral springs mounted upon metallic slats which extend across the frame and are secured at their ends to op- 55 posite members thereof. These slats are also of sheet-metal pressed into form and have integral upwardly-turned flanges at their lat-

eral edges. The width of these slats is increased at intervals throughout their lengths at the points of support of the spiral springs, so that the flanges at the lateral edges curve about these points of support and partially 60 surround the bases of the springs; in this way, the springs mounted upon the slats are also held against lateral movement.

One embodiment of the invention is illus- 65 trated in the accompanying drawings, in which

Figure 1 is a section of a portion of a cushion; Fig. 2 is a plan view of the frame broken away in part; and Fig. 3 is a detail view in section on line 3—3 of Fig. 2, illustrating the 70 construction of one of the slats.

Referring to these drawings, the frame consists of metallic side-members 1, 1, and end-members 2, 2, which are secured together at their ends to form a rectangular 75 frame. Certain of the frame-members are of sheet-metal pressed to a channel-section. The cross-section preferred is that shown in Fig. 1, from which, it will be seen that the frame-member consists of a base portion 3, 80 sides 4, 4, a flange 5 at the inner edge, and an extension 6 at the outer edge, the latter being bent outwardly and then downwardly to form a groove at the outer edge of the frame-member opening downwardly. This groove 85 is adapted to receive a strip of wood 7, to which the covering material of the cushion may be secured by tacks 8.

In order to strengthen the frame-members 1, 1, a plurality of sheet-metal braces 9 are 90 employed, extending transversely of the frame-members and each secured at one end to the flange 5 and at the other end to the extension 6. In the form of cushion shown in the drawings, only the side-members 1, 1, 95 of the frame are formed of sheet-metal, the end-members 2, 2, being castings. These end-members have grooves formed therein to receive tacking strips similar to those in the side-members and aline at their ends with the grooves in the side-members. Each of the end-members 2, 2, has integral offsets 10, formed on one side thereof, one at either end, each of these being adapted to enter the end of one of the side members 1, 1, and to be secured thereto in any suitable manner as by means of rivets.

Each of the frame-members 1, 1, and 2, 2, supports a line of spiral springs. The springs 111, supported upon the sheet-metal frame-

members 1, 1, are secured upon the base portions 3 thereof. It will be seen that by reason of this manner of supporting these springs, the latter may be of increased length. The springs 11 are of such size that they fit snugly between the sides 4, 4, of the frame-members. The springs 11 on the frame-members 2, 2, may be secured to the latter in any desired manner, as by bending 10 the ends of the springs downwardly and inserting and soldering them in openings formed in the frame-members; also staples may be employed for holding the springs in position, these staples entering openings in the 15 frame-members and being secured therein.

Extending across the frame and secured at their ends to opposite frame-members, are a plurality of slats 12, each of which supports a line of spiral springs 13. These slats are 20 also of sheet-metal pressed into form to provide upwardly-turned flanges 14 at the lateral edges thereof, to give them increased strength. Each of these slats is of greatest width at the points of support of the springs 25 13 mounted thereon, and is curved about these points somewhat, so that between each pair of adjacent springs it is of least width. In this way, a plurality of seats for the springs 13 are formed and the flanges 14 at the lateral 30 edges of the slats form walls which coact with the spiral springs to prevent lateral movement thereof. At each end of each of the slats 12, an upwardly-turned integral wall 15 is provided to facilitate securing the 35 ends of the slats to the sides 4 of opposite side-members by means of rivets 16.

Secured to the upper end of the springs 11 and 13 in each line across the cushion is a flat steel spring 17, the ends of which are downwardly turned, and over each of these flat springs is laid a strip of coarse fabric 18. A covering 19, usually termed the "first canvas" is then drawn over the top of the cushion and its edges carried down under the 45 frame, where they are secured to the strips 7 by means of tacks. Upholstery material 20 is then laid over this covering and the outer covering 21 is then applied over the cushion, its edges being similarly carried down under the edges of the frame, where they are secured 50 to the strips 7 by tacks.

Having now described our invention, what we claim as new therein and desire to secure by Letters Patent is as follows:—

55 1. A cushion having a rectangular frame consisting of metallic frame-members secured together at their ends, certain of said frame-members being sheet-metal strips pressed to a channel-section and arranged with the open side upward, slats extending across said frame and secured at their ends to opposite members thereof, spiral springs mounted within the channels of said frame-members and extending upwardly there- 60

65 from, spiral springs mounted on said slats,

and a covering extending over said springs and yieldingly sustained thereby, substantially as set forth.

2. A cushion having a frame consisting of metallic frame-members secured together at 70 their ends, certain of said frame-members being sheet-metal strips pressed to a channel-section and arranged with the open side upward, said members having extensions at the outer sides bent to form grooves, tacking 75 strips secured in said grooves, spiral springs mounted within the channels of said frame-members and extending upwardly therefrom, and a covering yieldingly positioned by said springs and secured at its edges to said strips, 80 substantially as set forth.

3. A cushion having a frame consisting of metallic frame-members secured together at 85 their ends, certain of said frame-members being sheet-metal strips pressed to a channel-section and arranged with the open side upward, metallic slats having integral, upwardly-turned flanges at their lateral edges extending across said frame and secured at their ends to opposite frame-members, spiral 90 springs mounted within said frame-members and slats and extending upwardly therefrom, and a covering yieldingly sustained by said springs, substantially as set forth.

4. A cushion having a frame consisting of 95 frame-members secured together at their ends, certain of said members being sheet-metal strips pressed to a channel-section, metallic braces extending across each of said members and secured at their ends to opposite sides thereof, spiral springs supported 100 on said members, and a covering yieldingly sustained by said springs, substantially as set forth.

5. A cushion having a frame consisting of 105 frame-members secured together at their ends, certain of said members being sheet-metal strips pressed to a channel-section and arranged with the open side upward, metallic braces extending across each of said 110 sheet-metal members and secured at their ends to opposite sides thereof, spiral springs mounted within said channel-shaped members and extending upwardly therefrom, and a covering yieldingly sustained by said 115 springs, substantially as set forth.

6. A cushion having a frame consisting of frame-members secured together at their ends, certain of said members being sheet-metal strips pressed to a channel-section and 120 to provide a flange at the inner edge and an extension at the outer edge forming a groove, a tacking strip in said groove, metallic braces extending across said members and secured at one end to said flange and at the other to 125 said extension, spiral springs supported on said members, and a covering yieldingly sustained by said springs, substantially as set forth.

7. A cushion having a rectangular frame 130

consisting of side and end members, said side members being sheet-metal strips pressed to a channel-section and said end members being castings having integral offsets at their 5 ends entering the ends of said side members and secured thereto, each of said frame-members having a lengthwise groove formed therein, strips in said grooves, springs supported on said frame-members, and a covering 10 sustained by said springs and secured at its edges to said strips, substantially as set forth.

8. A cushion having a rectangular frame consisting of frame-members secured together at their ends, slats extending across said frame and secured at their ends to opposite frame-members, said slats consisting of sheet-metal strips pressed to provide horizontally disposed body portions and flanges at 15 the lateral edges of the body portions extending upwardly at substantially a right angle thereto, spiral springs mounted on said slats and extending upwardly therefrom, the lowest convolution of each of said springs 20 resting on and being secured to the body portion of one of said slats between the flanges thereof, and said flanges being curved about the points of support of said springs, and a covering yieldingly sustained by said springs, 25 substantially as set forth.

9. A cushion having a frame, slats extending across said frame and secured at their ends to opposite members thereof, said slats consisting of sheet-metal strips pressed to provide 30 integral upwardly-turned flanges at the lateral edges, spiral springs mounted on said slats and extending upwardly therefrom, the lowest convolution of each of said springs resting on and secured to the body portion of 35 one of said slats between the flanges thereon 40 substantially as set forth.

and said slats being of greater width at the points of support of said springs than intermediate such points, and a covering yieldingly positioned by said springs, substantially as set forth.

45

10. A cushion having a rectangular frame consisting of side and end members, said side members being sheet-metal strips pressed to a channel-section and arranged with the open side upward and said end members being 50 castings having integral offsets at their ends entering the ends of said side members and secured thereto, each of said frame-members having a lengthwise groove formed therein, strips in said grooves, spiral springs mounted 55 within said channel-shaped members and extending upwardly therefrom, and a covering sustained by said springs and secured at its edges to said strips, substantially as set forth.

11. A cushion having a frame consisting of 60 metallic frame-members secured together at their ends, certain of said frame-members being sheet-metal strips pressed to a channel section and arranged with the open side upward, said members each having a groove 65 formed in the outer side thereof, tacking strips secured in said grooves, spiral springs mounted within the channels of said frame-members and extending upwardly therefrom, a covering yieldingly sustained by said 70 springs, and means for securing the edges of said covering to said strips, substantially as set forth.

This specification signed and witnessed this 22nd day of June, 1907.
